DESIGN FOR A COMBINED LAMP AND RADIO RECEIVING SET

Daniel J. Crowley, Grosse Pointe, Mich.

Application February 3, 1941, Serial No. 98,708

Term of patent 14 years

To all whom it may concern:

Be it known that I, Daniel J. Crowley, a citizen of the United States of America, residing at Grosse Pointe, in the county of Wayne and State of Michigan, have invented a certain new, original, and ornamental Design for a Combined Lamp and Radio Receiving Set, of which the following is a specification, reference being had to the accompanying drawing, forming a part thereof, wherein

Figure 1 is a side elevational view showing my new design of a combined lamp and radio receiving set; and

Figure 2 is a section taken substantially on

the plane indicated by the line 2—2 of Fig. 1.

The combined lamp and radio receiving set of my new design is substantially symmetrical about a vertical axis and the side opposite the one shown in Figure 1 is the same in appearance with the exception that the window exposing the station indicating dial is omitted.

The dominant features of my new design are shown in full lines in the drawing.

I claim:

The ornamental design for a combined lamp and radio receiving set, substantially as shown and described.

DANIEL J. CROWLEY.
